(57) **CLAIM**

We claim the ornamental design for a mounting system for mounting audio/visual devices or the like, as shown and described.

DESCRIPTION

FIG. 1 is a top isometric view of an embodiment of the claimed design;

FIG. 2 is a front elevational view of the claimed design of FIG. 1;

FIG. 3 is a rear elevational view of the claimed design of FIG. 1;

FIG. 4 is a top plan view of the claimed design of FIG. 1;

FIG. 5 is a bottom plan view of the claimed design of FIG. 1;

FIG. 6 is a right side elevational view of the claimed design of FIG. 1; and,

FIG. 7 is a left side elevational view of the claimed design of FIG. 1.

The ornamental design which is claimed is shown in solid lines in the drawings. The broken lines in the drawings are for illustrative purposes only and form no part of the claimed design. Break lines are used in particular locations to indicate that no specific length is being claimed.
